WALL TILE CLIP

Edward P. Lockart, Toledo, Ohio, assignor to
Owens-Illinois Glass Company, a corporation
of Ohio

Application December 18, 1940, Serial No. 370,662

4 Claims. (Cl. 72—19)

The present invention relates to improved means for supporting wall tile or the like and relates more particularly to novel means for rigidly and removably securing tile sections to wall surfaces of any suitable construction.

It has become common practice to construct wall surfaces both interior and exterior, from materials which are preformed in various shapes and thickness such as square or oblong blocks, tiles, slabs, sheets or plates. The material employed may be of any suitable substance such as stone, glass or other ceramic tile, depending upon the desired final effect. Generally in walls of such construction the elements are of a size which may be readily handled for installation and which are economical when it becomes necessary to replace one of the tiles. The dimensions of such tiles may be roughly 6"x 6" and usually not more than 1" thick inasmuch as they are employed only as a facing for the wall and not as a part of the supporting structure.

It is an object of the present invention to provide novel means for attaching such wall tiles to a prepared wall surface.

Another object of the invention is the provision of new and practical tile holding means adapted to be placed at the corner of the tile for supporting and spacing adjacent tiles.

A further object is the provision of a unit clip for resiliently retaining wall tiles in position in such manner that any tile may be removed or replaced without disturbing adjacent tiles.

A further object of the invention is the provision of wall tile retaining clips mounted in spaced relation upon a supporting means for positively aligning the tiles.

A still further object is the provision of a tile supporting and retaining clip which is economical and simple to manufacture and easily handled for installation.

Other objects will be in part apparent and in part pointed out hereinafter.

In the drawing:

Fig. 1 is a perspective view of a portion of a wall structure embodying my invention.

Fig. 2 is a plan view of the tile holder forming the subject of the present invention.

Fig. 3 is a vertical sectional view through the holder and the wall structure to which it is attached, the view being taken on line 3—3 of Fig. 2.

Fig. 4 is a perspective view of the holder.

Fig. 5 is a rear elevational view of the holder in assembled relation with several tiles.

Fig. 6 is a sectional plan view of a modified form of my invention.

The use of wall tiles as a decorating medium for both interior and exterior wall structures, has become increasingly popular due to the wide variety of materials available. The tiles may be successfully employed either as a part of new wall construction or they may be readily applied to existing walls. As a particular example, walls 10 which are frequently subjected to excessive moisture such as bath and shower rooms, may be surfaced with a water-proof tile which when bonded together, present a sealed leak-proof surface.

Fig. 1 of the drawing illustrates a portion of a supporting wall surface 8 which may be of any suitable construction which will present a supporting surface at least adjacent the area of the vertical meeting edges of the tiles. Wall surface tiles ordinarily do not form a part of the supporting structure of the wall and therefore may be of relatively thin and light weight construction. A base member 9 which forms the foundation or support for the lower course of tiles is suitably secured to the wall surface and a series of tile holders 10 or clips are spaced thereon.

Each clip 10 is formed from a rectangular sheet of a preferably non-corrosive metal having a semi-rigid quality which permits of a slight resiliency in the finished article as will be brought out hereinafter. The sheet (Fig. 4) is bent to form a body portion 11, in the form of an incomplete cylinder, the longitudinal edge portions 12 thereof being bent substantially radially outward in the form of flanges disposed in parallel spaced relation. The flanges 12 are cut as at 13 to form pairs of tabs 14 which are bent outwardly beyond the perpendicular to an inclined position. The tabs provide the means whereby tiles 15 are centered and uniformly spaced as will be presently described.

The clip is attached to the wall by means of a nail 16 extending through a medial opening 17 in the cylindrical portion and an opening 18 in the lower edge portion between the tabs. Thus the nail may be driven into the wall in a downwardly directed manner while maintaining the clip in substantially horizontal position. Nail openings 19 in the wall of the cylindrical portion, provide additional means for securing the clip.

One form of tile 15 with which the present clip may well be employed is illustrated in the drawings. Each edge 20 of the tile is provided with a groove 21 which with the oppositely disposed

groove in the edge of the adjoining tile, forms an annular channel. These channels extend around the tiles and the cylindrical bodies 11 of the clips are seated therein. In normal installation of tiles with the present form of clip, the lowermost row of clips is placed on the base member 9 and according to prevailing conditions, it may be necessary to unbend the lower tabs 14 so that the clips will lie in the proper position for setting the tiles. The width of the tiles regulates the spacing of the clips. Each succeeding tile (Fig. 5) is placed with the lower rounded corner in contact with one of the upwardly extending tabs 14 thereby spacing it a predetermined distance from the adjacent tile. As course is laid upon course, the clips perform the function of suspending and retaining the tiles at each corner as shown in Fig. 5. The cylindrical or body portion of the clip by its engagement within the groove, securely holds the tiles in properly spaced relation so that when a caulking compound 22 is placed within the crevices or joints between the tiles, the points will produce a uniform appearance.

A modified form of my invention is illustrated in Fig. 6. The clips 10 are mounted on a continuous cord 23 and spaced according to the size of the tile with which it is to be used. The cord may be treated with a waterproofing material or otherwise treated to prevent deterioration, since it forms a backing against which caulking material is forced. When the cord is employed, the space between the tiles is thus partially filled thereby considerably reducing the volume of caulking material needed.

When a tile becomes defaced or cracked, it may be readily broken or pried out and a new one substituted by simply forcing the tile against the clips until they spring apart and then snap into the grooves 21.

Modifications may be resorted to within the spirit and scope of the appended claims.

I claim:

1. A corner clip for holding rectangular wall tiles having grooves in the edges thereof, said clip comprising a substantially cylindrical portion for engaging in the grooves on the horizontal edges of the tiles, said clip including spaced parallel edge engaging portions for supporting and spacing superposed tiles at the corners thereof, and means forming a part of said edge portions for maintaining uniform horizontal spacing of the tiles, said clip including aligned openings to accommodate a fastening element.

2. A corner clip for holding rectangular wall tiles having grooves in the edges thereof, said clip comprising a substantially cylindrical portion for engaging in the grooves on the horizontal edges of the tiles, said clip including spaced parallel edge engaging portions for supporting and spacing superposed tiles at the corners thereof, and means forming a part of said edge portions for maintaining uniform horizontal spacing of the tiles, said clip including aligned openings to accommodate a fastening element.

3. In a clip of the character described, an elongated substantially cylindrical body formed of resilient sheet metal and including a pair of longitudinal parallel spaced flanges and a pair of inclined tabs struck outwardly from longitudinally spaced points on each flange, said body portion having a radial opening to accommodate anchoring means for the clip.

4. In a clip of the character described, an elongated substantially cylindrical body formed of resilient sheet metal and including a pair of longitudinal parallel spaced flanges and a pair of inclined tabs struck outwardly from longitudinally spaced points on each flange, and said body portion and one of the flanges having aligned openings to accommodate anchoring means for the clip.

EDWARD P. LOCKART.
